UNITED STATES PATENT OFFICE.

FRED ELLIOTT YOUNGS, OF DETROIT, MICHIGAN, ASSIGNOR TO EQUITABLE METER COMPANY, OF PITTSBURG, PENNSYLVANIA, A CORPORATION.

GAS-CONTROLLER.

971,099.

Specification of Letters Patent. Patented Sept. 27, 1910.

Application filed May 29, 1909. Serial No. 499,089.

To all whom it may concern:

Be it known that I, FRED E. YOUNGS, residing at Detroit, in the county of Wayne and State of Michigan, a citizen of the 5 United States, have invented or discovered certain new and useful Improvements in Gas-Controllers, of which improvements the following is a specification.

It is customary to provide means to supplement the protection afforded by the regulator to prevent excessive pressure of gas in 10 house service lines. The regulator is constructed and adjusted to maintain while operative a predetermined safe pressure in the 15 service lines, but provision should be made to prevent excessive pressure in service lines in case the regulator fails to operate.

The invention described herein has for its 20 object the provision of an outlet from the chamber of the regulator connected to the supply and service pipes, such outlet being normally closed by a liquid seal.

The invention is hereinafter more fully described and claimed.

25 In the accompanying drawing forming a part of this specification is shown in sectional elevation a regulator embodying my improvements.

The body portion 1 of the regulator is 30 formed with a regulating chamber A, an inlet chamber B and a relief chamber C, so arranged with reference to the regulating chamber as to permit of a controlled connection between said chambers. In the construction shown, a passage 2, which may be 35 an extension or enlargement of the regulating chamber extends under the relief chamber. In that portion of the passage or extension 2, a cup 3 is arranged said 40 cup being made preferably in the form of a hollow metal plug externally threaded so as to be removably secured in the under wall of the passage or extension. A tube 4 extends from the relief chamber down into 45 mercury contained in the cup 3, the depth of immersion being dependent upon the maximum pressure to be maintained in the regulating chamber A. When the pressure in this chamber exceeds a predetermined 50 maximum, the mercury will be forced from the cup into the tube, uncovering the lower end of the tube. Whereupon there will be a sudden rush of gas up through the mercury into the relief chamber, which has a 55 free outlet port 5, preferably connected by

a pipe to the atmosphere. In this sudden rush of gas through the mercury contained in the tube a considerable quantity of mercury may be carried up into the relief chamber and some will be carried out of the latter 60 unless provision is made to prevent such loss. To that end a baffle-plate 6 is arranged above and in line with the tube 4 where it opens into the relief chamber. This baffle-plate 6 is preferably hollowed or re- 65 cessed as is indicated in the drawing, to the end that the mercury which may be thrown up against it by the gas rushing into the relief chamber may the more certainly be baffled or thrown back to the bottom of the 70 chamber. And the bottom of this relief chamber is, as the drawing indicates, preferably hollowed or sloped downward to the point where the tube 4 opens into it, that the mercury which has been baffled back by 75 the baffle C shall be carried directly back through the tube 4 into the cup 3.

The gas entering the relief chamber passes 80 through a passage 7 above and behind the baffle plate to the escape orifice 5, and in addition there is another recess or baffle surface 11 in the upper wall of this relief chamber, and this baffle surface 11 also is hollowed as the drawing shows. The passage 7 lies between the two baffle surfaces 6 and 85 11. The purpose of the baffle surface 11 is supplemental and it will readily be understood. If there is no such surface, the stream of gas flowing out through the passage 7 might readily carry with it the mercury which had been thrown up against the baffle 6 and then thrown back into the stream, but with the supplemental baffle 11 any mercury which may thus be thrown 90 back from the baffle 6 and carried up along 95 the bottom of the chamber by the flowing stream is caught in the baffle 11, and there relieved of the impulse of the flowing stream, and is thrown down again on the bottom of the relief chamber. However, 100 the gas having lost a great part of its velocity by expansion in the relief chamber, will flow laterally into and along the passage and the pipe connected to the outlet port 5.

The controlling or regulating mechanism 105 in the chamber A may be of any suitable construction, but preferably such as is described and claimed in an application Ser. No. 479,123, filed February 20, 1909. The diaphragm 8 is held in place by the cover 9 110

in the usual or any suitable manner and the chamber between the diaphragm and cover is connected by a port 10 to the relief chamber as shown.

5 I claim herein as my invention:

1. A regulator case or shell provided internally with a regulating chamber and a relief chamber, the regulator chamber extending beneath the relief chamber and separated therefrom by a transversely extending partition, in combination with a mercury cup arranged in the regulating chamber, and a tube extending from the relief chamber through said partition and into said

15 cup, substantially as described.

2. A regulator case or shell provided internally with a regulating chamber, a relief chamber, and a diaphragm chamber, com-

munication from said regulating chamber through a liquid seal to said relief chamber, 20 the entrance to said relief chamber being centrally disposed in the bottom thereof, a baffle plate and two orifices arranged in the roof of said relief chamber, one of said orifices leading to the diaphragm chamber and 25 the other to an escape, the said baffle plate arranged centrally between the two said orifices and protecting both from splashing liquid, substantially as described.

In testimony whereof, I have hereunto 30 set my hand.

FRED ELLIOTT YOUNGS.
